H. B. JEWELL AND L. L. MINVILLE.

CRATE FASTENER.

APPLICATION FILED SEPT. 23, 1921.

1,431,809.

Patented Oct. 10, 1922.

UNITED STATES PATENT OFFICE.

HARRY BERNARD JEWELL AND LEONARD LAURENT MINVIELLE, OF NEW IBERIA,
LOUISIANA.

CRATE FASTENER.

Application filed September 23, 1921. Serial No. 502,780.

To all whom it may concern:

Be it known that we, HARRY BERNARD JEWELL and LEONARD LAURENT MINVIELLE, citizens of the United States, residing at 5 New Iberia, in the parish of Iberia and State of Louisiana, have invented certain new and useful Improvements in Crate Fasteners; and we do hereby declare the following to be a full, clear, and exact description of the 10 invention, such as will enable others skilled in the art to which it appertains to make and use the same.

Our invention relates to improvements in shipping crates, and it is intended to provide a crate of a knocked-down or semi-knocked-down type, which may be conveniently shipped in compact form and set up in place when in use, and which may be sealed and opened from the top without 20 any other injury to the crate than breaking the seal.

Our invention will be more fully understood after reference to the accompanying drawings, in which like parts are indicated 25 by similar reference symbols throughout the several views, and in which:—

Figure 1 is a perspective view of the complete crate, the parts being in the assembled relation and the seal applied, but the contents of the crate being omitted.

Figure 2 is an end view of the upper portion of the crate as seen from the left of Fig. 1, the parts being shown on a larger scale than in said figure.

Figure 3 shows a section along the line 3—3 of Fig. 2, and looking in the direction of the arrows.

Figure 4 is a similar view to Fig. 2, but shows the fastening means released and the 40 seal removed, and with the top in a slightly raised position and the fastening rod turned down.

Figure 5 shows a section along the line 5—5 of Fig. 4, and looking in the direction 45 of the arrows; and

Figure 6 is a rear view of the upper portion of the top of the crate.

The crate comprises two sides A and A', each made of a series of wooden slats *a* and 50 *a'* hinged by the wires D to the ends of the wooden slats *b* and *b'* comprising the ends B and B' of the crate. If desired

one or more central partitions C may be provided with a series of transverse slats *c*, hinged by the wires D' to the side slats *a* 55 and *a'*, respectively. These wires D and D' have their ends preferably clinched over as shown at *d*.

The bottom E of the crate is preferably formed of a series of slats *e* secured to the 60 braces E', and the ends of the bottom are secured to the ends B and B', as by nailing or in any other convenient way.

The top F consists of a plurality of slats *f* secured together by braces *f'*, and this top 65 is hinged as at G to one end of the crate, such as B'. The hinges are preferably mounted below the top as shown in Figs. 1 and 6.

The other end of the top, which projects 70 slightly beyond the end of the crate, is provided with fastening plates H, preferably mounted beneath the top, as shown in Figs. 1 to 5. The free ends of these plates are bent downwards and terminate in 75 tongues *h*, shown most clearly in Figs. 3 and 5. These plates H are secured to the top in any convenient way, as by means of the nails *h'*, see Figs. 3 and 5.

The tongues *h* engage beneath the loops *m* 80 of the fastening rod M, which rod is journaled in the bearing plates N, see Fig. 5. In order to hold this rod in the normally engaged position, and close against the end of the crate, as shown in Figs. 2 and 3, we 85 provide springs O, one end of each of which engages in a loop *m'* formed in the rod M, and the other end engages the bearing plate P secured to the upper part of the end B of the crate.

The fastening rod M is provided at its center with a loop *m*°, which is adapted to swing over the eye bolt Q, which eye bolt is provided with the eye *q* through which a wire seal R of suitable type is inserted. 95 When this seal is in place, it will prevent the rod from swinging outwards and will hold the loops *m* in engagement with the tongues *h*, as shown in Figs. 1 and 2. When the seal is removed, the fastening rod M 100 may be swung back to the position shown in Fig. 4, and the cover may be swung open as indicated in Figs. 4 and 5.

The rod may be conveniently turned by

providing the handles m^2 , in the form of loops which may be conveniently grasped by the operator in the operation of swinging the fastening rod from the position shown in Fig. 2 to that shown in Fig. 4.

It will be seen that the body portion of the crate may be shipped in the knocked-down condition, and the top and bottom may be put together and the whole shipped as either one bundle, or two bundles, and when it is desired to set up same the body portion is swung to the proper position, the bottom is nailed on, and then the top hinges are secured to the end B', and the crate is ready for use.

When the crate is filled ready for shipment, the top is swung down to the lowered position; the fastening rod M is swung by hand outward to clear the tongues h, and is then permitted to swing to the position shown in Fig. 2, under the action of the springs O, and the seal is applied.

As long as the seal remains in place, the crate cannot be opened without breaking some of the parts; but as soon as the seal is removed the fastening rod M may be swung to the released position and the top may be raised or lowered as desired.

While we have shown the invention as applied to a collapsible fruit or vegetable crate, it may be applied to any species of container intended for re-use, having a hinged cover in which locking and sealing means for said cover may be required.

It will be obvious that various modifications might be made in the herein described apparatus, and in the construction, combination and arrangement of parts which could be used without departing from the spirit of our invention; and we do not mean to limit the invention to such details except as particularly pointed out in the claims.

Having thus described our invention what we claim and desire to secure by Letters Patent of the United States is:—

1. The combination with a crate provided with a collapsible body portion, and a bottom secured thereto, of a cover hinged at one end to said body portion, and provided at the other end with a plurality of fastening plates each having a tongue projecting below the edge of the cover, a fastening rod pivoted to said body portion below said tongues and provided with loops adapted to swing over and engage said tongues, means for automatically swinging said rod to the position for engaging said loops with said tongues, and means for locking said rod in the position for holding said loops in engagement with said tongues.

2. The combination with a crate provided with a body portion, and a bottom secured thereto, of a cover hinged at one end to said body portion, and provided at the other end with a plurality of fastening plates each

having tongues projecting below the edge of the cover, a fastening rod pivoted to said body portion below said tongues and provided with loops adapted to swing over and engage said tongues, means for automatically swinging said rod to the position for engaging said loops with said tongues, and means for locking said rod in the position for holding said loops in engagement with said tongues, said last mentioned means comprising an eye bolt secured to the end of the crate adjacent said rod, a loop provided in said rod and adapted to swing over said eye-bolt when the rod is in the engaging position for fastening the crate, and a stop passed through said eye-bolt and locking said rod against swinging outwards.

3. The combination with a crate provided with a body, of a cover hinged at one end to said body portion, and provided at the other end with a plurality of fastening plates each having a tongue projecting below the edge of the cover, a fastening rod pivoted to said body portion below said tongues and provided with loops adapted to swing over and engage said tongues, coil springs automatically swinging said rod to the position for engaging said loops with said tongues, and means for locking said rod in the position for holding said loops in engagement with said tongues, said last mentioned means comprising an eye-bolt secured to the end of the crate adjacent said rod, a loop provided in said rod and adapted to swing over said eye-bolt when the rod is in the engaging position for fastening the crate, and a wire seal passed through said eye-bolt and locking said rod against swinging outwards.

4. The combination with a crate provided with a body portion, and a bottom secured thereto, of a cover hinged at one end to said body portion, and provided at the other end with a plurality of fastening plates each having a tongue projecting below the edge of the cover, a fastening rod pivoted to said body portion below said tongues and provided with loops adapted to swing over and engage said tongues, and also with loops forming handles for turning rod, means for automatically swinging said rod to the position for engaging said loops with said tongues, and means for locking said rod in the position for holding said loops in engagement with said tongues.

5. The combination with a crate provided with a body portion, of a cover hinged at one end to said body portion, and provided at the other end with a plurality of fastening plates each having a tongue, projecting below the edge of the cover, a fastening rod pivoted to said body portion below said tongues and provided with loops adapted to swing over and engage said tongues, and also with loops forming handles for turning

rod, means for automatically swinging said rod to the position for engaging said loops with said tongues, and means for locking said rod in the position for holding said loops in engagement with said tongues, said last mentioned means comprising an eye-bolt secured to the end of the crate adjacent said rod, a loop provided in said rod and adapted

to swing over said eye-bolt when the rod is in the engaging position for fastening the 10 crate, and a stop passed through said eye-bolt and locking said rod against swinging outwards.
